(57) **CLAIM**

I claim the ornamental design for a radio, as shown and described.

DESCRIPTION

FIG. 1 is a top, front perspective view of the radio of the present invention;

FIG. 2 is a top, rear perspective view of the radio of FIG. 1;

FIG. 3 is a front elevation view of the radio of FIG. 1;

FIG. 4 is a rear elevation view of the radio of FIG. 1;

FIG. 5 is a top plan view of the radio of FIG. 1;

FIG. 6 is a right side elevation view, the left side view being a mirror image, of the radio of FIG. 1; and,

FIG. 7 is a top, rear perspective view of the radio of FIG. 1 showing the base portion housing a radio with volume, AM/FM, station and ON/OFF control buttons/switches, and the doors in an open position.

1 Claim, 4 Drawing Sheets
